UNITED STATES PATENT OFFICE.

WILLIAM M. BROWN, OF DETROIT, MICHIGAN.

DOOR-HOLDER.

1,149,424.

Specification of Letters Patent. Patented Aug. 10, 1915.

Application filed May 3, 1915. Serial No. 25,515.

To all whom it may concern:

Be it known that I, WILLIAM M. BROWN, a citizen of the United States, residing at Detroit, in the county of Wayne and State 5 of Michigan, have invented certain new and useful Improvements in Door-Holders, of which the following is a specification.

This invention relates to door holders of that type suitable for use in connection with 10 swinging doors, such as doors of garages, barns and the like, but capable of use in other relations if desired.

The device provides a combined door stop and holder, and comprises a post which is 15 set in the ground and which acts as a stop, and is provided with one or two swinging arms to hold one or two doors as desired, which arms can be swung up or down to engage or disengage the doors.

20 The device can be cheaply constructed of ordinary pipe stock and fittings.

In the accompanying drawings Figures 1 and 2 are side elevations of the device of the 25 double type, that is, having two arms. Fig. 3 is a perspective illustrating the manner of use.

Referring specifically to the drawings, 6 indicates a post, which may be made of two pipe sections united by a fitting 7. This fitting will be a cross fitting where two arms 30 are used, or a T fitting where one arm is

used. The post is set in the ground, or in a cement or wooden base 8, to about the depth of the fitting 7. The arms 9 are pivoted in the fitting 7, conveniently by ring nuts 10, 35 the arms being angular as shown, and the joint being preferably tight enough to hold the arm in upright position, and the arms can be conveniently made of small pipe sections connected by an elbow. The ends of 40 the post and the arms are finished by caps 12.

In use, the post forms a stop for the door, which may be held open by swinging up the arm, the door being held between the post and the arm. Two adjacent doors may be 45 held open, on opposite sides of the post, by the double armed device shown.

I claim:

A door holder and stop comprising a post 50 consisting of upper and lower sections and an angle fitting connecting the same, the upper section projecting into the path of the door to form a stop for the same, and an angular arm having a horizontal part pivotally connected to the fitting. 55

In testimony whereof, I affix my signature in presence of two witnesses.

WILLIAM M. BROWN.

Witnesses:

CHARLES E. WESTAWAY,
IDA HAGEN.
